(57) CLAIM

The ornamental design for a hair clipper with interchangeable heads, as shown and described.

DESCRIPTION

The broken lines in the drawings are for environmental purposes only and form no part of the claimed design.
